US0D1034554S

(12) **United States Design Patent** (10) **Patent No.:** **US D1,034,554 S**
(45) **Date of Patent:** ** *Jul. 9, 2024

(54) **DISPLAY MOUNT**

(71) Applicant: **CKnapp Sales, Inc.**, Goodfield, IL
(US)

(72) Inventor: **Micah Fehr**, Danvers, IL (US)

(73) Assignee: **CKnapp Sales, Inc.**, Goodfield, IL
(US)

(*) Notice: This patent is subject to a terminal disclaimer.

(**) Term: **15 Years**

(21) Appl. No.: **29/687,126**

(22) Filed: **Apr. 10, 2019**

(51) LOC (14) Cl. **14-02**

(52) U.S. Cl.

USPC **D14/447**

(58) **Field of Classification Search**

USPC D14/125-134, 239, 125-129, 251-253,
D14/335, 336-337, 371-382, 439-441,

D14/432, 447-452, 457, 492

CPC E02F 3/3604; E02F 3/3613; E02F 3/3627;
E02F 3/364; E02F 3/3663

(57) **CLAIM**

The ornamental design for a display mount, as shown and described.

DESCRIPTION

FIG. 1 is a perspective view of a display mount, showing my new design.

FIG. 2 is a front view of the display mount of FIG. 1.

FIG. 3 is a rear view of the display mount of FIG. 1.

FIG. 4 is a top view of the display mount of FIG. 1.

FIG. 5 is a bottom view of the display mount of FIG. 1.

FIG. 6 is a first side view of the display mount of FIG. 1; and,

FIG. 7 is a second side view of the display mount of FIG. 1. The features of the display mount shown in broken lines form no part of the claimed design.

1 Claim, 7 Drawing Sheets
